US00D955908S

(12) **United States Design Patent** (10) Patent No.: **US D955,908 S**
(45) Date of Patent: **** Jun. 28, 2022**

(54) **SPECTROMETER**

(71) Applicant: **TrinamiX GmbH**, Ludwigshafen am Rhein (DE)

(72) Inventor: **Karsten Kueber**, Offenbach am Main (DE)

(**) Term: **15 Years**

(21) Appl. No.: **35/511,853**

(22) Filed: **Nov. 11, 2020**

(80) **Hague Agreement Data**

Int. Filing Date: **Nov. 11, 2020**

Int. Reg. No.: **DM/211410**

Int. Reg. Date: **Nov. 11, 2020**

Int. Reg. Pub. Date: **May 14, 2021**

(51) LOC (13) Cl. **10-04**

(52) U.S. Cl.

USPC **D10/75**

(58) **Field of Classification Search**

USPC D10/47, 78; D24/216

CPC G01J 3/0205; G01J 3/0272; A61B 5/14542

Linksquare spectrometer, <https://linksquare.io/order/> (Year: 2017).*

* cited by examiner

Primary Examiner — George D. Kirschbaum

(57) **CLAIM**

The ornamental design for a spectrometer, as shown and described.

DESCRIPTION

1. Spectrometer

1.1 : Perspective

1.2 : Front

1.3 : Back

1.4 : Left

1.5 : Right

1.6 : Top

1.7 : Bottom

The representations of the design are in greyscale; the design does not claim protection for a specific coloring.
